ABSTRACT: An automatic return-to-center deflection circuit develops a deflection signal that linearly increases from a minimum value to a maximum value and deflects a scanning beam in a display device from a first extreme position to a second extreme position. When the deflection signal reaches its predetermined maximum value, the scanning beam is automatically retracted to the center or midpoint position between the first and second extreme positions. The scanning beam is then retracted in a second step to the first extreme position when a new scanning cycle is initiated.

AUTOMATIC RETURN-TO-CENTER DEFLECTION CIRCUIT

BACKGROUND OF THE INVENTION

Display devices are utilized to provide a visual display of data being written into or read from a computer. A display terminal usually includes both a display device and a character generator along with the associated control circuitry therefor. In a display terminal, there is usually one character generator for each display device and frequently the character generator is integrally united with the display device. However, it is frequently desirable to make the character generator a separate entity from the display device and then have a plurality of display devices operated from a single character generator.

In one particular system, a monoscope tube is utilized as the character generator and a plurality of display devices are operated therefrom. A monoscope generates one character at a time. Therefore, in order to display different characters on a plurality of different display devices, it is necessary to couple the monoscope to the different display devices in succession. Furthermore, to avoid complexity, monoscopes typically generate each separate character in the same amount of time. Consequently, there is a maximum number of characters that can be generated by a monoscope in any practical system and the maximum number of characters must be divided proportionately for each display device, when a plurality of display devices are operated simultaneously. For example, when four display devices are operated simultaneously each receives one quarter of the maximum number of characters available, etc. For operating efficiency, the display devices are paired with each other so that when one display device displays characters, the scanning beam in the other display device is retracted. Heretofore, the scanning beam was retracted to its initial extreme deflection position to remain in a standby condition until a new line of characters was to be displayed. Since most energy in a scanning beam is dissipated while standing by in such an extreme deflection position, a lot of energy is wasted.

SUMMARY OF THE INVENTION

A return-to-center deflection circuit for a display device embodying the invention includes deflection means for providing a deflection signal that linearly increases from a minimum value to a maximum value to deflect a scanning beam in said device from a first extreme position to a second extreme position. First retrace means are included in the device for retracing the scanning beam in one step from the said second extreme position to a center rest position located substantially midway between the first and second extreme positions after the deflection signal reaches its maximum value. Second retrace means are included in the device for retracing the scanning beam in a second step from said center position to the first extreme position at the beginning of a new scanning cycle. linearly BRIEF DESCRIPTION OF THE DRAWINGS

FIG. 1 is an overall block diagram of a video data terminal including a detailed schematic circuit diagram of a deflection circuit embodying the invention;

FIG. 2 is a graphical representation of a series of signal waveforms that are helpful in understanding the operation of the deflection circuit in FIG. 1; and

FIG. 3 is a detailed schematic circuit diagram of another deflection circuit embodying the invention.

DETAILED DESCRIPTION

Referring to FIG. 1 there is shown a display terminal 10 that includes a deflection circuit 12 embodying the invention. A character generator 14 which may, for example, include a monoscope tube, as well as the associated control circuitry therefor, generates video signals that represent characters,

which are then applied to a display device 16. The display device 16 may, for example, comprise a cathode ray tube, that includes a face 18 for displaying the characters. A scanning beam 20, which emanates from a cathode 22 in the tube 16, is directed to impinge against the phosphor on the inside of the face 18 so as to produce a light spot 24 thereon. The scanning spot 24 is deflected by X direction (i.e. horizontal) and Y direction (i.e. vertical) deflection coils 26 and 28. The X and Y deflection coils 26 and 28 are coarse deflection coils. Characters are formed on the face 18 by additionally superimposing onto the scanning beam 20 a "tickler" deflection signal by means of a tickler coil (not shown) which deflects the scanning spot 24 up and down in a rapid motion. The character generator 14 turns the scanning beam 20 on and off at predetermined points during this "tickler" deflection to create each character by a plurality of vertical slices. As a consequence, characters 30, such as the capital letter T, are formed on the face 18 of the display device 16. The synchronizing signals for deflection in the X direction are obtained from the character generator 14 and applied to the X direction deflection circuit 12. The output deflection in the deflection circuit 12 are AC (i.e. alternating current) coupled via a capacitor 32 to a variable gain amplifier 34 and thence to the X deflection coil 26. Similarly, the character generator 14 also supplies the synchronizing signals to a Y direction deflection circuit 12'. The deflection circuit 12' is similar to the deflection circuit 12 except for the fact that since this is a Y direction deflection circuit, the circuit 12' is operated with different time constants because there will be many horizontal scan cycles for each vertical scan cycle. The vertical deflection circuit 12' is AC coupled via capacitor 36 to a variable gain amplifier 38 and thence to the Y direction deflection coil 28. A power supply 40 is coupled to supply the power to the various circuits in the video data terminal 10.

Referring now in more detail to the deflection circuit 12, this circuit includes deflection means 39 for developing a deflection signal that linearly increases from a minimum value 40 to a maximum value to cause the scanning spot 24 to deflect from an extreme left position to an extreme right position on the face 18 of the tube 16. The deflection means 39 includes a reactive circuit element 42 that is coupled to be charged by a constant current source 44. The reactive circuit element 42 is illustrated in FIG. 1 as a capacitor which is charged by a current source. In accordance with the principle of duality, the reactive circuit element may also comprise an inductor that is coupled to be charged by a constant voltage source. The current source 44 is shown variable to denote that different currents may be supplied to the reactive circuit element 42 when different pluralities of display devices are coupled to the character generator 14.

First retrace means 45 is included in the deflection circuit 12 to retrace the scanning beam 20 from an extreme right-hand position on the face 18 of the display device 16 back to the center of the face. The first retrace means includes a pair of complementary transistors 46 and 48 of opposite conductivity types. The first transistor 46, which is of PNP-type conductivity, includes an input emitter electrode 47 that is coupled to the constant current source 44 and an output collector electrode 50 that is coupled through a resistor 52 to a terminal 54 supplying a negative potential $-V_1$. The collector electrode 50 is also coupled through a resistor 56 to the base electrode 58 of the second transistor 48. The second transistor 48 is of NPN-type conductivity and includes an emitter electrode 60 that is coupled to the terminal 54 as well as a collector electrode 62 that is coupled to one terminal 54 as well as a collector electrode 62 that is coupled to one terminal 64 of a voltage divider 66. The voltage divider 66 includes a pair of resistors 68 and 70 that are coupled between the divider terminal 64 and a terminal 72 that supplies the positive potential $+V_2$. The midpoint 71 of the voltage divider 66, which is the junction of the resistors 68 and 70, is coupled to the base electrode 74 of the first transistor 46.

Second retrace means 75 is included in the deflection circuit 12 to retrace the scanning beam 20 from the center of the face 18 to the left side thereof. The second retrace means 75 includes a transistor 80 of the NPN-type conductivity. The transistor 80 includes an emitter electrode 82 coupled to the negative potential terminal 54 and a collector electrode 84 coupled through a resistor 86 to the junction of the capacitor 42 and the emitter electrode of the transistor 46. Thus, the second retrace means 75 is directly shunted across the capacitor 42. Synchronizing signals that are derived from the character generator 14 are applied through a resistor 88 to the second retrace means 75 at the beginning of each scanning cycle.

OPERATION

In describing the operation of the deflection circuit 12 of FIG. 1, reference will be made to the waveforms 90 and 92. The waveform 92 in FIG. 2 is the synchronizing signal applied from the character generator to initiate the scanning cycle. The waveform 90 comprises the X direction deflection signal that is developed across the reactive circuit element 42 and applied via the capacitor 32 and the amplifier 34 to the X direction deflection coil 36.

It is assumed that operation begins at the time t_1 shown in FIG. 2. At this time t_1 all of the transistors 46, 48 and 80 in the deflection circuit 12 are off or nonconducting. Consequently, the current derived from constant current source 44 is applied to the reactive circuit element 42. The reactive circuit element 42 therefore develops a linearly increasing voltage that increases from a minimum value of amplitude A_1 to a maximum value of amplitude A_3 . This linearly increasing portion of the waveform 90 causes the scanning beam to deflect 20 to deflect from an extreme left side position of the display face 18 to an extreme right side position thereof. Of course, superimposed on this deflection is the "tickler" deflection signal which produces individual slices or scans of characters in a plurality of vertical deflections.

When the maximum value A_3 is reached, 12 of transistor 46 becomes forward biased and is rendered conductive. This is because the potential $+V_2$ is selected such that the maximum value A_3 exceeds the potential $+V_2$ by the emitter-base voltage drop of the transistor 46. The transistor 46 in conducting diverts a portion of the current from the source 44 away from the reactive circuit element 42 and the base 58 of the transistor 48 is therefore raised from the negative potential level $-V_1$ and the base-emitter junction becomes forward biased. The transistor 48 therefore also turns on and the current flow through the transistor 48 produces a voltage drop in the voltage divider 66. This voltage drop reduces the potential at the base of the transistor 46 which in turn diverts a larger portion of the current from the source 44 away from the reactive circuit element 42. The interconnections of the transistors 46 and 48 provide a regenerative feedback path that rapidly increases the current flow through both transistors and partially discharges the reactive circuit element 42. Such a discharge is shown by the portion of the waveform 92 between the times t_2 and t_3 .

At the time t_3 , the transistors 48 saturates and the voltage across this transistor 48 becomes substantially fixed at a relatively small magnitude. The base 74 of the transistor 46 is therefore held fixed at a potential determined by the voltage divider 66. The resistance value of the voltage divider are selected to hold the transistor 46 conducting in a desired manner. The voltage across the reactive circuit element 42 is therefore fixed at the amplitude A_2 , which is substantially midway between A_1 and A_3 , as shown in FIG. 2. The scanning beam 20 is therefore positioned at the center of the tube 16 midway between the left and right extreme positions of deflection on the display face 18. At this point, no power is being utilized in the X deflection coil 26. Any tendency for the voltage across the reactive circuit element 42 to change is counteracted by the transistors 46 and 48. The transistors 46 and

48 therefore exhibit a voltage regulation between the times t_3 and t_4 . Such a voltage regulation effectively converts the constant current source 44 into a constant voltage source, which maintains the scanning beam fixed at the center rest position 5 of the display device 16.

At the time t_4 , a synchronizing pulse 100 (FIG. 2) derived from the character generator 14 is applied to the base electrode of the transistor 80 in the circuit 12. The synchronizing pulse 100 is effective to deflect the scanning beam 20 from the center rest position to the extreme left position of the display face 18 so that a new scanning cycle is initiated. The synchronizing pulse 100 forward biases and turns on the transistor 80 to effectively convert the transistor 80 into a closed switch across the reactive circuit element 42. The transistor 80 therefore discharges the reactive circuit element 42. Such a discharge is shown by the portion of the waveform 90 between the times t_4 and t_5 . During this discharge, the drop in voltage across the capacitor 42 reverse biases the emitter-base junction of the transistor 46 and turns off this transistor. The turnoff of the transistor 46 also turns off the transistor 48. Consequently, the current from the constant current source 44 is diverted through the transistor 80. The width of the synchronizing pulse 100 is selected such that the pulse ends 15 when the reactive circuit element discharges to the minimum value of voltage A_1 . When the synchronizing pulse 100 terminates, the transistor 80 is rendered nonconductive. At this point, all the transistors 46, 48 and 80 are nonconductive and a new scanning cycle has begun.

20 It is to be noted that the return-to-center of the scanning beams 20 during retrace reduces the power dissipation in the X deflection coil 26. Such a reduction permits a smaller power supply 40 to be utilized in the terminal 10 when a plurality of devices are operated simultaneously.

25 It is also to be noted that the variable feature of the current source 44 permits changes in the time it takes for the capacitor 42 to charge from the value A_1 to the value A_3 . Increasing the current from the source 44 causes the capacitor 42 to charge more rapidly to the magnitude A_3 , as shown by the dotted deflection waveform 90a in FIG. 2. The number of characters that can be displayed on the display device 16 is therefore reduced since the scanning beam 20 sweeps from the extreme left side position to the extreme right side position more rapidly than is the case with the deflection waveform 90.

30 Reducing the current from the source 44 causes the capacitor 42 to charge more slowly to the value A_3 , as shown by the dotted waveform 90b in FIG. 2. More characters can therefore be displayed on the display device 16. Consequently more or less display devices can be operated simultaneously from the same character reference generator 14. Of course, the repetition rate of the retrace pulse 100 in the waveform 92 also varies to correspond to the changes in the current generator 44. Regardless of the time it takes the capacitor 42 to charge to 35 the magnitude A_3 , the deflection circuit 12 still returns the scanning beam 20 to the center standby position when the magnitude A_1 is reached.

35 This increase or decrease in the number of characters displayed is substantially independent of the gain exhibited by the amplifier 34. Heretofore, scanline time and character 40 number changes were accomplished by changing the gain of an amplifier, (e.g. amplifier 34) which in turn affected the centering of the scanning beam 20. A readjustment of the centering control in turn affected the gain. Further adjustments and readjustments were therefore necessary. Such adjustments and readjustments are obviated by utilizing the deflection circuit 12.

45 It is also to be noted that the deflection circuit 12 renders the display terminal 10 "operator proof." If the operator forgets to adjust the synchronizing pulses 100 when more or less display devices are added to or subtracted from the data terminal 10, no harm is done to the terminal 10. This is because no resultant displacement of the scanning beam 20 can occur when the deflection waveforms 90 are AC coupled through 50 the capacitor 32 to the display device 16.

55 It is also to be noted that the deflection circuit 12 renders the display terminal 10 "operator proof." If the operator forgets to adjust the synchronizing pulses 100 when more or less display devices are added to or subtracted from the data terminal 10, no harm is done to the terminal 10. This is because no resultant displacement of the scanning beam 20 can occur when the deflection waveforms 90 are AC coupled through 60 the capacitor 32 to the display device 16.

In FIG. 3 there is shown another embodiment of the deflection circuit 12. In FIG. 3 parts corresponding to those in FIG. 2 are given the same reference numerals but the numerals are primed. The values and types of components are also shown in FIG. 3. It is to be noted that the constant current source 44 comprises a transistor 110 that is coupled through a potentiometer 112 and a resistor 114 to a positive potential supply $+V_3$. The potentiometer 112 has a plurality of taps labeled 2, 4, 6 and 8 for adjusting the deflection limits when 2, 4, 6, and 8 display devices are operated in one terminal. The base of the transistor 110 is also coupled through a resistor 116 to the positive potential $+V_3$. A pair of oppositely poled diodes 118 and 120 are coupled between the voltage divider 66' and the collector of the transistor 110. The diode 120 prevents current from the voltage supply $+V_2$ from flowing into the capacitor 42' and the diode 118 maintains the correct potentials on the transistor 46'. The output of the reactive circuit element 42' is coupled through a two-stage emitter-follower amplifier circuit comprising the transistors 122 and 124.

Thus, in accordance with the invention, a return-to-center deflection circuit is provided which enables a video data terminal to operate a plurality of display devices from one character generator without large power dissipation. The deflection circuit also provides the ability to choose a wide variety of scan times with essentially constant power dissipation. Furthermore, extreme flexibility is provided by the simple controls in the circuit which maintains minimal power dissipation regardless of system timing charges or operator adjustment errors.

I claim:

1. A deflection circuit for a display device that includes a scanning beam, comprising in combination:
 deflection means for developing a deflection signal that linearly increases from a minimum value to a maximum value to deflect said scanning beam from a first extreme position on said display device to a second extreme position;
 first retrace means for retracing scanning beam in a first step from said second extreme position to a center position substantially midway between the first and second extreme positions when said deflection signal reaches said maximum value; and
 second retrace means for retracing the scanning beam in a second step from said center position to said first extreme

45

position at the beginning of a scanning cycle.

2. The combination in accordance with claim 1 wherein said deflection means includes:

5 a reactive circuit element for developing said deflection signal that is applied to deflect said scanning beam; and means for applying substantially constant valued signal to said reactive circuit element to charge said reactive element to develop a substantially linearly increasing deflection signal.

10 3. The combination in accordance with claim 2 that further includes:

means for altering the magnitudes of said substantially constant valued signal to change the time it takes to deflect said scanning beam from said first extreme position to said second extreme position.

15 4. The combination in accordance with claim 2 wherein said first retrace means includes a regulation circuit that is coupled to the reactive circuit element to be operated when said reactive circuit element charges to said maximum value so as to discharge said reactive circuit element to a value substantially midway between said minimum and maximum values to maintain said reactive circuit element at said midway value.

20 5. The combination in accordance with claim 4 wherein said second retrace means includes a switching element coupled across said reactive circuit element to be operated to close at the beginning of a scanning cycle to discharge said reactive circuit element to said first minimum value so as to retrace said scanning beam to said first extreme position.

25 6. The combination in accordance with claim 4 wherein said regulation circuit includes first and second complementary transistors with each including base, emitter and collector electrodes.

30 7. The combination in accordance with claim 6 wherein said regulation circuit further includes:

means for coupling the collector emitter of said first transistor to the base electrode of said second transistor; a voltage divider coupled between a point of fixed potential and the collector electrode of said second transistor;

means for coupling the base electrode of the first transistor to point of said voltage divider; and

means for coupling said reactive circuit element from the emitter electrode of said first transistor to the emitter electrode of said second complementary transistor.
